INVENTOR:
LOREN RISK

BY *Whitley and Buckman*

ATTORNEYS.

UNITED STATES PATENT OFFICE.

LOREN RISK, OF MINNEAPOLIS, MINNESOTA

COMBINATION HEATING TOOL.

Application filed October 29, 1923. Serial No. 671,335.

To all whom it may concern:

Be it known that I, LOREN RISK, a citizen of the United States, residing at Minneapolis, in the county of Hennepin and 5 State of Minnesota, have invented certain new and useful Improvements in Combination Heating Tools, of which the following is a specification.

My invention relates to combination heating tools, and an object is to provide a device in which flat fuses may be placed and ignited for the purpose of heating the tool. Although not limited to such use, my tool is particularly adapted for use in applying 10 patches to material such as inner tubes of pneumatic tires. I have found that when the surface to be repaired is heated just prior to the application of the cement and the patch, much less time is required before 15 the article is ready for use. In fact, with the use of my invention, the article is ready for use as soon as the patch is applied while the patch adheres much more firmly than when applied in the old way.

20 An object in particular is to provide a tool which may be used for heating the material which is to be repaired and which may also be used for heating patches and cement. Another object is to provide a 25 tool having means carried thereby for buffing the material to be repaired.

The full objects and advantages of my invention will appear in connection with the detailed description, and the novel features 30 of my inventive idea will be particularly pointed out in the claims.

In the accompanying drawings which illustrate one form in which my invention may be embodied, Fig. 1 is a perspective 35 view of the tool with a small portion broken away. Fig. 1^a is a detail view in section on the line 1^a 1^a of Fig. 1. Fig. 2 is a view in section on the line 2—2 of Fig. 1, showing one manner in which the tool may be 40 used. Fig. 3 is a perspective view of one form of fuse which may be used in the tool. Fig. 4 is a perspective view of another form of fuse. Fig. 5 is a view in section on the line 5—5 of Fig. 1.

45 This application is a continuation in part of my prior application which matured into Patent No. 1,475,029 dated November 20, 1923.

50 Referring to the construction shown in the drawings, the numeral 10 designates the body portion of the tool, this tool be-

ing in the form of a shallow receptacle having perforations 12 in its walls near the bottom thereof. A cover 14 is hinged to the rear of the body member by pins 16. The 60 cover is adapted to fit into the receptacle 10, and it has a bottom member provided with upstanding walls around the margin thereof. The upstanding walls at their upper ends are turned outwardly to provide 65 horizontal side flanges 18 and an extended front horizontal flange 20, these flanges limiting the extent to which the cover can be pushed into the receptacle 10. The extended flange 20 is provided with a plurality of upwardly extending teeth 22 which 70 constitute a buffer or scraper. Secured to the rear of the receptacle 10 is tang 24, the rear end of which is received in an opening in a handle 26. The tank 24 at the end 75 where it is attached to the rear wall of the receptacle has a width nearly equal to the length of said wall and gradually tapers towards its other end. This tang is reinforced by downwardly bent side flanges 80 28 and an intermediately downwardly bent rib 30.

In the use of my tool, the cover 14 is placed in open position as shown in dotted lines in Fig. 1, and solid fuel is placed 85 in the receptacle 10. This solid fuel is in the form of fuses such as the fuses F and F', shown in Figs. 3 and 4. These fuses after they are placed in the receptacle are ignited and the cover is closed, the smoke 90 and gas escaping from the perforations 12 and the flanges 18 and 20 serving to prevent upward movement of the flame which issues from the perforations. The fuses continue to glow and keep the tool hot for 95 a considerable period of time. My tool is particularly adapted for use in applying patches to articles which are to be repaired. When used for this purpose, the surface to be repaired is cleaned and roughened by 100 the use of the buffer having the teeth 22 and is then washed with suitable liquid such as gasoline or benzine. The surface thus prepared is heated by the use of the hot tool and then a specially prepared cement is applied to the heated surface of 105 the material which is being repaired, and is also preferably applied to the heated surface of the patch. In the drawings, S designates the surface of the article which 110 is being repaired while the patch is indicated by the character P. The patch pre-

vious to its application may be heated by placing it in the depression of the cover 14 or if of larger size, may be heated by rubbing the hot tool over the patch. The cover may also be employed as a pan for heating certain kinds of cement. It is to be noted that the flanges aid materially in the operation of the device, and that the flange 20 has the three-fold function of serving as a buffer, preventing the upward movement of flames issuing from the front perforations in the receptacle, and limiting the extent to which the cover can be depressed into the receptacle.

15 I claim:

1. A combination heating tool comprising a shallow receptacle for receiving flat fuses, said receptacle having perforations in its vertical walls for escape of smoke and gas, a cover hinged to said receptacle, flanges extending horizontally from said cover so as to be disposed above said perforations, and a handle attached to said receptacle.

25 2. A combination heating tool comprising a shallow receptacle for receiving flat fuses, said receptacle having perforations in its vertical walls for escape of smoke and gas, a cover hinged to said receptacle, 30 said cover having vertical walls which fit

closely within the vertical walls of said receptacle when the cover is closed, and having a bottom member connecting the vertical walls of the cover at their lower margins, so as to provide a shallow space 35 for the fuses, and a handle attached to said receptacle.

3. A combination heating tool comprising a shallow receptacle for receiving flat fuses, a cover hinged to said receptacle and adapted to fit down into the latter when closed, 40 a flange extending horizontally from said cover, teeth on said flange for buffing purposes, and a handle attached to said receptacle.

4. A combination heating tool comprising a shallow receptacle for receiving flat fuses, said receptacle having perforations in its vertical walls for escape of smoke and gas, a cover hinged to said receptacle and adapted to fit down into the latter when closed, 50 flanges extending horizontally from said cover so as to be disposed above said perforations, teeth on one of said flanges for buffing purposes, and a handle attached to 55 said receptacle.

In testimony whereof I hereunto affix my signature.

LOREN RISK.
